(57) **CLAIM**

The ornamental design for a duster with interior sleeve with end cap, as shown and described.

DESCRIPTION

FIG. 1 is a perspective view of the duster with interior sleeve with end cap;

FIG. 2 is a perspective view of the duster with interior sleeve with end cap illustrated in FIG. 1 showing the placement of the end cap;

FIG. 3 is an exploded perspective view of the duster with interior sleeve with end cap illustrated in FIG. 1;

FIG. 4 is a top plan view of the duster with interior sleeve with end cap illustrated in FIG. 1 with the bottom plan view being a mirror image of the top plan view;

FIG. 5 is a first side view of the duster with interior sleeve with end cap illustrated in FIG. 1, with the second side view being a mirror image of the first side view;

FIG. 6 is a front end elevation view of the duster with interior sleeve with end cap illustrated in FIG. 1; and,

FIG. 7 is a back end elevation view of the duster with interior sleeve with end cap illustrated in FIG. 1.

The duster with interior sleeve with end cap includes two internal sheets forming a pocket with an opening on the front end for receiving a portion of a handle and the opposing end including an end cap. The pocket is sandwiched between two duster elements. The two internal sheets are shown as having a different color than the two duster elements and the end cap is shown as having a color different than the two internal sheets. The broken lines illustrated in FIG. 1 form no part of the claim.
